Inc., Cincinnati, Ohio, a corporation of New York

Application January 3, 1956, Serial No. 39,581

Term of patent 14 years

(Cl. D89—1)

FIG. 1

FIG. 2

Figure 1 is a front perspective view of a food mixer motor unit showing my new design.

Figure 2 is a perspective view showing the second side and the top thereof.

The side of the food mixer motor unit not illustrated is substantially identical to that one which is shown in Figure 2 and the bottom thereof is substantially plain.

I claim:

The ornamental design for a food mixer motor unit, substantially as shown and described.
